CHAIR SEAT

Clarence W. White, North Bennington, Vt., assignor to H. C. White Company, North Bennington, Vt., a corporation of Vermont

Application April 9, 1932, Serial No. 604,150

4 Claims. (Cl. 155—140)

The present invention relates to furniture and more particularly to the seats of chairs, settees and the like, and especially to such furniture of the folding type.

It is an object of the invention to provide a seating surface of flexible fabric, the seating area of which is relatively high at the forward and rear portions and relatively low therebetween, the forward seating surface being curved forwardly and downwardly and so constructed that the desired conformation of the seat will be maintained over a long period of time despite constant use.

In the folding type of furniture, it has been customary to provide a relatively flat fabric seating surface. Where the forward edge has been reinforced by some relatively rigid material, such as a wooden stretcher, such stretcher has resulted in discomfort to the occupant by reason of this hard and uncomfortable wooden portion striking him under the knees.

This objection has been avoided, in some instances, by supporting the seating fabric on substantially parallel spaced side rails alone, with no front rail and no rear rail, so that in folding, instead of the front and rear rails being movable toward each other, the side rails are movable upwardly toward each other, folding the seating fabric centrally from front to rear.

Such chairs, however, have not provided any comfort comparable to that provided by upholstered furniture and, moreover, the forward portion of the flat fabric seating surface has sagged more and more with continued use in a direction tending to slide the occupant forwardly and downwardly out of the chair.

In such cases, no yieldable forward reinforcement will prevent the forward portion of the seat from sagging downwardly, at least to some undesirable extent, in the life of the chair, particularly where it is frequently used, and, as already pointed out, the provision of a wooden or similar rail on the forward edge of the seat detracts seriously from its utility as a comfortable piece of furniture.

In accordance with the present invention, there is provided in this class of furniture a seating surface comparable in comfort to upholstered furniture, and, moreover, one which has a yielding reinforcement at the forward edge of the seating surface, as a result of which the seat may be folded upon itself.

More specifically, the invention includes, among other features, such a reinforcement that prevents the forward edge of the seating surface

from sagging lower than the lowest portion to the rear thereof, accomplishing this in such a manner that comfortable yieldability is maintained without a tendency to cause wrinkling of the forward edge of the seating surface, with the result that, even with continued use and allowing for the normal fabric stretch, the comfort provided by the seating surface and substantially its original conformation are both maintained.

Other objects and advantages of the invention, including the elimination of edge wear heretofore occurring at the forward edge of substantially flat fabric seats not provided with a front rail or similar relatively non-yielding support, as well as the surface wear caused in prior known chairs that are provided with such relatively rigid supports, will appear from the following description, taken in connection with the accompanying drawings, in which:

Figure 1 is a front elevation of a folding chair embodying the invention;

Figure 2 is a horizontal sectional view through the chair of Figure 1, taken on the line 2—2 of said figure;

Figure 3 is a vertical longitudinal sectional view, taken on the line 3—3 of Figure 1;

Figure 4 is a substantially central vertical sectional view, taken from left to right through the chair of Figure 1, with the parts in folded position; and

Figure 5 is a perspective view of one of the chair seat side rails.

Referring in detail to the accompanying drawings, the invention herein is illustrated as being embodied in a chair providing a single seat, though it will be understood that the invention is equally applicable to a wider piece of furniture, such as a settee, providing seating surface for more than one person.

In the embodiment herein shown, a pair of spaced chair side frames are provided, each including a front leg 10, back leg 12 and upper and lower chair frame side rails 14 and 16 respectively, connecting the front leg with the back leg. An arm 18 is supported at its forward end by the front leg 10 and at its rear by the back leg 12, an arm corner brace 20 being provided if desired and a lateral arm brace 22 being similarly provided. A front leg corner brace 24 and back leg corner brace 26 may connect the front and back legs respectively with the lower chair rail 16. Upper back leg corner brace 28 may connect the back leg 12 and upper chair rail 14.

These two chair frames are movable from the operative position of Figure 1 to the folded posi-

tion of Figure 4, which latter figure shows the parts in nearly completely folded position. When in the position of Figure 1, the back rest fabric 30 is stretched substantially taut, while in the folded position of Figure 4 the back fabric folds upon itself. Each end of this fabric is securely fastened to the upper portion of one of the back legs 12, as indicated in Figure 3.

Between the two side frames is movably and foldably located the seat of the chair and, in accordance with the invention, a seat rail 40 is provided with a raised forward portion 42 and a forwardly and downwardly convexly-curved front end 44. The raised portion 42 of the seat rail is higher than the intermediate portion 46 to the rear thereof, and, toward or at the rear of the seat rail, a rear raised portion 48 is preferably provided.

Each seat rail is connected to one of the chair side frames by connecting means, such as the crossed connector frame members 50, whose lower ends are pivotally attached, as at 52, to the side frames and whose upper ends are rigidly fixed to the seat rails 40. Intermediate their ends, each adjacent pair of cross frame members 50 is provided with a pivot 54 so that the opposite chair rails and their connecting frames are inter-pivoted by the two pins or other pivot means 54.

Suitable abutment stops 60, herein shown as being in the form of hooks, are provided in connection with the side frames for the seat rails 40 to bear upon when in the position of Figure 1, where the seat is in operative or unfolded position.

35 A seat-forming fabric portion 62 has its opposite sides secured to the seat rails 40 and is stretched between and on said seat rails sufficiently to cause it to conform to the upper seat rail surface where the seating fabric 62 contacts therewith. Between the lower portions 46 of the rails the seat-forming fabric 52 will, particularly after continued use, be somewhat lower in the center, as indicated at 68 in Figure 3.

The forward portion 70 of the seating fabric 62 contacts with the portions 44 of the seat rails, being similarly curved forwardly and downwardly, and between the front ends of the seat rails the front portion 70 of the seating fabric is stretched substantially taut.

50 While the intermediate portion of the seat may be permitted to stretch within limits, it is desirable that the forward raised portion 72 of the seat be prevented from stretching or sagging to such an extent that the comfort provided by this foldable seat is materially lessened. Accordingly, this portion of the seat is reinforced in such a manner that undesirable sagging is prevented, while at the same time nothing rigid, such as prior suggested wooden rails, is provided which might detract from the comfort of the occupant; also, the reinforcement is so constructed and arranged that it also tends to prevent wrinkling at the forward or front raised and curved part of the seat.

55 As shown in the drawings, the lower edge of the seat-forming fabric is folded under itself and curved upwardly and rearwardly (Figure 3), lying in curved contact with the underside of the seating surface, as indicated at 76 in Figures 2 and 3.

In seats of the present type, it is essential that the foldability of the seat be maintained, so that its flexibility must not be destroyed, while at the same time undue sagging must be prevented.

75 Too much rigidity at the front of the seat would

also prevent the lower forward end, which extends downwardly, from being yieldable toward the rear of the seat, which yieldability is provided by the present invention, thus greatly increasing the comfort of the occupant of the chair.

80 All of the aforementioned desirable results are secured and maintained, as herein shown, by securing the folded-under or reinforcing fabric portion 76 in curved contact with the underside of the seating surface by means of spaced-apart, substantially parallel rows of stitches, as indicated in dot and dash lines in Figures 1 and 2. This leaves the intermediate portion of the seat to the rear of the front raised portion with more flexibility than the front part of the seat, and, as indicated in Figure 3, the folded-under portion 76 is preferably in secure contact with the forwardly and downwardly curved front end 44 of the seat rail 40.

85 The construction described provides, in a folding chair of the fabric seating surface type, a seating surface comparable in comfort with the seating surfaces provided by upholstered seat frames with both front and rear rails as well as side rails, and with the construction described, 90 the comfortable conformation of the seating surface is maintained despite constant use.

95 What is claimed is:

1. A folding chair including side frames movable toward and away from each other, a pair of substantially parallel seat rails movable toward and away from each other between said side frames, means pivotally attaching each of said seat rails to one of said side frames and to each other, a seat-forming fabric portion having its front end curved forwardly and downwardly and being flexible and centrally foldable between its opposite sides, and a similarly curved, flexible and foldable reinforcing fabric portion sewed in contact with the forwardly and downwardly curved front end of said seat-forming fabric portion by spaced rows of stitches through said forwardly and downwardly curved front end.

105 2. A folding chair including side frames movable toward and away from each other, a pair of substantially parallel seat rails movable toward and away from each other between said side frames and having their forward ends curved forwardly and downwardly, means pivotally attaching each of said seat rails to one of said side frames and to each other, a seat-forming fabric portion having opposite sides secured to said seat rails and having its front end curved forwardly and downwardly, said seat-forming fabric portion being centrally foldable by movement of said seat rails toward each other, and a similarly curved and foldable reinforcing fabric portion sewed beneath and in contact with the forwardly and downwardly curved front end of said seat-forming fabric portion by spaced rows of stitches through said curved front end, both fabric portions being rearwardly yieldable between said seat rails.

110 3. A folding chair including side frames movable toward and away from each other, a pair of substantially parallel seat rails, movable toward and away from each other, between said side frames and each having a raised portion near its forward end, the forward ends of said seat rails curving downwardly from their raised portions, 115 means pivotally attaching each of said seat rails to one of said side frames and to each other, a seat-forming fabric portion having opposite sides secured to said seat rails and having a raised portion near its front end and its front end

curved forwardly and downwardly from said raised portion over the forward ends of said seat rails, said seat-forming fabric portion being centrally foldable by movement of said seat rails 5 toward each other, a portion of said seat-forming fabric being, at the forward end of the seat, folded under itself, extending upwardly and rearwardly and sewed in curved contact with the curved front end of the seat-forming portion by 10 substantially parallel rows of stitches, both the folded under portion and the seat-forming portion, at the forward end of the seat, being rearwardly yieldable between said seat rails.

4. A folding chair including side frames movable toward and away from each other, a pair of substantially parallel seat rails, movable toward and away from each other, between said side frames and each having a raised portion near its forward end, the forward ends of said seat rails 20 curving downwardly from their raised portions, means pivotally attaching said seat rails to said

side frames and to each other, a seat-forming fabric portion secured at opposite sides to said seat rails and having a raised portion near its front end and its front end curved forwardly and downwardly from its raised portion over the forward ends of said rails, said seat-forming fabric portion being centrally foldable by movement of said seat rails toward each other, a portion of said seat-forming fabric being, at the forward end of the seat, folded under itself and curving upwardly and rearwardly and being secured in curved contact to the forward ends of said seat rails and being sewed in curved contact with the curved front end of the seat-forming portion by substantially parallel rows of stitches extending laterally across and through both curved portions of said fabric, both of said portions, at the forward end of the seat, being rearwardly yieldable between said seat rails.
